UNITED STATES PATENT OFFICE.

GERHARD MARTIN THADEN, OF READING, PENNSYLVANIA.

BELL SUPPORT.

Application filed May 15, 1926. Serial No. 109,353.

This invention relates to supports for electric bells of the type as disclosed in my co-pending application.

The primary object of the present invention is to provide a supporting means for electric bells that is so designed to support the bell from a single nail, screw, or bolt and one which can be easily and quickly associated therewith.

10 A further object is to provide a supporting means for an electric bell which has a detachable connection with the base of the bell in a manner whereby it can be detached with very little effort if it is desired to have 15 access to the bell ringing means which is confined within the bell and base thereof.

This invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a front elevation of the bell 30 of the type which has my novel supporting means associated therewith.

Figure 2 is a side elevation of the bell and its supporting means in applied position.

Figure 3 is an enlarged rear elevation 35 showing the application of my supporting means with the bell.

Figure 4 is a fragmentary sectional view taken on line 4—4 of Figure 3.

Figure 5 is a fragmentary perspective 40 view showing one of the depressions of the supporting plate.

Figure 6 illustrates a part of the means for securing the plate to the base of the bell.

Referring to the drawings in detail the 45 reference numeral 1 indicates the base of the bell and an annular flange 2 is formed with said base in the manner as clearly illustrated in Figure 4.

Extending from diametrically opposite 50 sides of the flange 2 are studs 3 and 4 respectively while extending inwardly from the flange at a point diagonally opposite and centrally of the studs 3 and 4 is a stud 5 which as shown in Figure 3 is slightly wider 55 than the first mentioned studs.

The studs 3 and 4 have their inner surfaces

slightly inclined to provide cam surfaces and are adapted together with the stud 5 to secure the support plate 6 in association with the base and flange 2 thereof, and projecting from the plate at one edge thereof are spaced ears 7 and 8 which receive therebetween the stud 5 when the support plate 6 is associated with the base as shown. The support plate is recessed as at 9 and 10 upon opposite sides 60 with a portion of said plate depressed inwardly from the recesses to provide cam surfaces 11 and 12 as suggested in Figure 5 for cooperation with the cam surfaces of the studs 3 and 4 whereby the plate 6 may be positioned for cooperative association with the studs and held within the inner walls of the flange by the engagement of the stud 5 with the ears 7 and 8, the engagement of the cam surfaces of the depressions and studs 3 and 4 respectively and the curved edge of the plate with the flange as will be readily apparent. 65

The plate 6 is cut away and curved inwardly as at 13 and 14 to provide a finger 70 engaging projection 15 and the curved portions also provide a means of access to the binding nuts of the terminals of the bell as shown in Figure 3 without removing the plate. 75

A key hole shaped slot 16 is formed centrally in the plate 6 whereby the plate may be associated with a nail, screw, or other similar means in the manner as illustrated in Figure 4 of the drawings. 80

It is thought from the foregoing description that the advantages and novel features of my invention will be readily apparent. 85

I desire it to be understood that I may make changes in the construction and in the 90 combination and arrangement of the several parts, provided that such changes fall within the scope of the appended claims.

What I claim is:

1. The combination with an electric bell 100 and the base thereof, a flange formed on the base, studs extending inwardly from the flange, a plate adapted to be received between the inner edges of the flange and lie in the same plane therewith, ears formed on said plate for association with one of said studs, and depressions also formed on said plates for association with the other of said studs. 105

2. The combination with an electric bell 110 and its base, a flange formed with said base and extending rearwardly therefrom, of a

supporting means for said bell comprising a plate adapted to be received between the inner edges of said flange and to lie in the same plane therewith, studs projecting inwardly from diametrically opposite sides of said flange, a stud extending inwardly from said flange and in a line centrally of the studs first mentioned, said plate having a portion cut away and curved upon itself to

provide a finger engaging means, a pair of ears formed on said plate and associated with the stud second mentioned, and depressions also formed on said plate and being provided with cam surfaces adapted to be associated with cam surfaces formed on the diametrically oppositely disposed studs.

In testimony whereof I affix my signature.
GERHARD MARTIN THADEN.
